CLAIM

The ornamental design for a spray mop head, as shown and described.

DESCRIPTION

FIG. 1 is a perspective view taken from the top, front, and right side of a spray mop head showing our new design; FIG. 2 is a top plan view of the spray mop head shown in FIG. 1; FIG. 3 is a bottom view of the spray mop head shown in FIG. 1; FIG. 4 is a front elevational view of the spray mop head shown in FIG. 1; FIG. 5 is a rear elevational view of the spray mop head shown in FIG. 1; FIG. 6 is a left elevational side view of the spray mop head shown in FIG. 1; FIG. 7 is a right elevational side view of the spray mop head shown in FIG. 1; FIG. 8 is a perspective view taken from the top, front, and right side of a spray mop showing our new design; FIG. 9 is a top plan view of the spray mop shown in FIG. 8; FIG. 10 is a bottom view of the spray mop shown in FIG. 8; FIG. 11 is a front elevational view of the spray mop shown in FIG. 8; FIG. 12 is a rear elevational view of the spray mop shown in FIG. 8; FIG. 13 is a left elevational side view of the spray mop shown in FIG. 8; FIG. 14 is a right elevational side view of the spray mop shown in FIG. 8; FIG. 15 is a perspective view taken from the top, front, and right side of a spray mop bottle shown in a spray mop; FIG. 16 is a perspective view taken from the top, front, and right side of the spray mop bottle shown in FIG. 15;

FIG. 17 is a top plan view of the spray mop bottle shown in FIG. 15;

FIG. 18 is a bottom view of the spray mop bottle shown in FIG. 15;

FIG. 19 is a front elevational view of the spray mop bottle shown in FIG. 15;

FIG. 20 is a rear elevational view of the spray mop bottle shown in FIG. 15;

FIG. 21 is a left elevational side view of the spray mop bottle shown in FIG. 15;

FIG. 22 is a right elevational side view of the spray mop bottle shown in FIG. 15;

FIG. 23 is a perspective view taken from the top, front, and right side of a spray mop showing our new design;

FIG. 24 is a top plan view of the spray mop shown in FIG. 23; FIG. 25 is a bottom view of the spray mop shown in FIG. 23; FIG. 26 is a front elevational view of the spray mop shown in FIG. 23;

FIG. 27 is a rear elevational view of the spray mop shown in FIG. 23;

FIG. 28 is a left elevational side view of the spray mop shown in FIG. 23; and,

FIG. 29 is a right elevational side view of the spray mop shown in FIG. 23.

The broken lines are for illustration purposes only and form no part of the claimed design.
